Filed Dec. 28, 1961, Ser. No. 162,674

6 Claims. (Cl. 15—87)

This invention relates to an improved power sweeper and more particularly to a power sweeper of the riding type which is especially designed to sweep factory and institutional floors and similar large surfaces.

Sweepers of the general type with which the present invention is concerned are known in the art. Most of these sweepers have a large cylindrical broom which is rotated in contact with a surface to be swept on an axis which is parallel to the surface and perpendicular to the movement of the machine. Frequently, the sweepers have a side broom located to one side and in front of the sweeper to facilitate cleaning areas adjacent walls, curbs, or the like. However, such sweepers have had a number of shortcomings which the sweeper according to the present invention overcomes.

The side broom assembly on most sweepers is mounted in a manner such that it can be tilted about a horizontal axis to enable the broom to yield should it strike a wall or other object. However, when the broom tilts about the horizontal axis, the bristles tend to dig into the surface being swept, causing possible damage or at least excessive wear to the bristles and possible abrading or scratching of the surface. To overcome this problem, the side broom of the new sweeper is mounted on an arm which is capable of pivoting about a vertical axis spaced from the side broom so that the broom can yield and swing inwardly in a horizontal plane toward the sweeper if an obstruction is contacted. In this manner, the degree and extent of the contact of the bristles with the floor is virtually unchanged and neither the bristles nor the surface will be damaged by the contact. The driving arrangement for the side broom of the new sweeper is also designed to automatically change the amount of pressure of the broom on the surface when the level of the surface changes. Thus, should a shallow recess or drop in the surface level be encountered, the pressure on the broom will be increased to assure proper sweeping of this portion of the surface. Also, if a bump or rise in the surface be encountered, the pressure on the broom will be decreased to reduce the chance of abrading such surface and still enable adequate sweeping to take place. The side broom of the new machine can also swing automatically under the machine and out of the way when it is raised and not in use.

It is, therefore, a principal object of the invention to provide an improved power sweeper.

Another object of the invention is to provide a power sweeper which is capable of cleaning surfaces, and particularly uneven surfaces, more effectively than heretofore.

Still another object of the invention is to provide a power sweeper with less complicated controls which are easier to operate.

Yet a further object of the invention is to provide a power sweeper with a side broom which can yield when contacting an obstruction without damaging the bristles or the surface being swept.

Many other objects and advantages of the invention will be apparent from the following detailed description of a preferred embodiment thereof, reference being made to the accompanying drawings, in which:

FIG. 1 is an overall view in perspective of a riding-type power sweeper embodying the principles of the present invention;

2

FIG. 2 is an enlarged, detailed view in perspective of a side broom assembly of the sweeper shown in FIG. 1;

FIG. 3 is a side view in elevation with parts sectioned, of the side broom assembly shown in FIG. 2; and

FIG. 4 is an enlarged, fragmentary view in cross section taken along the line 4—4 of FIG. 2.

Referring to the drawings, and more particularly to FIG. 1, an overall power sweeping machine embodying the principles of the present invention is indicated by the numeral 20. The sweeper 20 includes a main frame or body 22 supported on a pair of driven, rear wheels 24 and a single, centrally located front wheel 26. The front wheel 26 is steered through suitable mechanism associated with a steering wheel 28 located in front of an operator's seat 30.

The sweeper 20 also includes a pair of headlights 32 which are particularly useful when factory aisles and similar other dark areas are being cleaned, the headlights 32 being mounted on an operator's panel 34. The panel 34 is supported on a deck 36 which constitutes part of the frame 22 with suitable foot controls being located just above the deck 36 behind the panel 34 for controlling the drive for the rear wheels 24 and also for stopping the sweeper. These controls can be of any suitable design, as is known in the art, and will not be discussed in any detail, except for a brake of the sweeper 20. To one side of the operator's seat 30 is a control board generally indicated at 38 containing a plurality of levers for controlling various elements of the sweeper 20 including the wheel transmission.

A side broom 40 is located under the front, right corner of the sweeper 20, this broom enabling the sweeper to clean closely to a wall or curb, for example, with the broom 40 sweeping the dirt toward the center of the sweeper 20. The sweeper can also be supplied with a similar side broom at the front, left corner, if desired.

The dirt swept to the center of the sweeper 20 by the broom 40, as well as other dirt passing under the sweeper 20, passes under a front flap 42 and is picked up by a main broom 44. The main broom 44 carries this dirt into a hopper 46 in which heavier dirt and debris is deposited, with lighter dirt particles being eventually passed through a plurality of filter bags 48 which collect the remaining dirt and allow the air to pass to the atmosphere. The dirt collected in the filter bags 48 can then be separated and removed by a novel shaker system, to be discussed later, and the hopper 46 can be unloaded by a novel dumping system, also to be discussed later.

With the various elements of the overall sweeper 20 having been briefly discussed above, the individual elements, beginning with the side broom 40, will now be described in detail. Referring to FIGS. 2-4, the broom 40 is of conventional construction, including relatively stiff bristles

50 mounted on a backing plate 52. The broom 40 is positioned so that the bristles 50 contact the area to be swept at a position of approximately 12-3 o'clock, taking the front of the broom 40 in the direction of travel of the sweeper 20, as being 12 o'clock. With this arrangement,

the broom 40 causes dirt contacted by the bristles 50 to be swept inwardly toward the center of the sweeper and at the same time the broom 40 is urged outwardly away from the sweeper. The broom 40 is fixed to a side broom shaft 54 which is located at a slight angle to the vertical to provide the above-described contact of the bristles 50. The shaft 54 is rotatably supported in a bearing housing 55 which is affixed to a first, generally horizontally-disposed, side broom arm 56 which is adjustably

65 affixed to a second, generally horizontally-disposed, side broom arm 58. The latter arm is integral with a yoke indicated at 60 which includes a web 62 and horizontally-

disposed fork plates 64 and 66. The plates 64 and 66 have annular walls or ridges 68 and 70 affixed thereto which encircle circular projections 72 and 74 of top and bottom walls 76 and 78 of a gear box or housing 80. The cooperation of the annular walls 68 and 70 with the projections 72 and 74 enable the yoke 60 and the arms 56 and 58 to be supported by the gear housing 80 yet enable the arms 56 and 58 to pivot in a horizontal plane with respect to the housing 80. The pivoting movement of the arms 56 and 58 is substantially parallel to the plane of rotation of the brush 40, except for the slight inclination which causes the brush to contact the surface at the 12-3 o'clock position. The gear housing 80 is supported for pivotal movement in a vertical plane on a horizontally-disposed, driven shaft 82 by suitable bearings 84. With this arrangement, the gear housing 80 can pivot around the shaft 82 in a vertical plane and thus move the arms 56 and 58 and the brush 40 toward and away from the surface.

The broom 40 and the shaft 54 are driven through side broom sheaves 86 attached thereto which, in turn, are rotated through belts 88 and side broom drive sheaves 90. The latter is affixed to a vertically-disposed worm shaft 92 (FIG. 4) which is rotatably held within the housing 80 by bearings 94 and 96 mounted in the top and bottom walls 76 and 78 and is positioned at the centers of the circular projections 72 and 74. Keyed to the shaft 92 is a worm gear 98 which meshes with a worm 100 affixed to the driven shaft 82. The driven shaft 82 is rotatably supported by bearing blocks 102 which, in turn, are supported on part of the frame 22, specifically on a wall 104 of the main broom chamber. The shaft 82 is driven through a drive sheave 106 which is suitably driven from an internal combustion engine 108 (FIG. 1) which constitutes the sole source of power for the entire sweeper 20.

The engine 108 drives the shaft 82 in a counterclockwise direction as indicated by the arrow in FIG. 2 and the shaft 82 also rotates the brush 40 in a counterclockwise direction, as indicated by the arrow, through the worm 100, the worm gear 98, the sheaves 90, the belts 88, and the sheaves 86. When the brush rotates in this manner, it tends to move the arms 56 and 58 in a clockwise direction around the pivots formed by the fork plates 64 and 66, with the broom 40 moving outwardly from the sweeper 20. The extent of this movement, however, is limited by means of a first chain or stop means 110 which is suitably affixed to an outer portion of the arm 56 and is also affixed to the under side of the deck 36 constituting part of the frame 22 at a point inwardly from the arm 56. Also, since the broom 40 is free to move downwardly in a vertical plane if it is not supported by the surface being swept, a second chain or stop means 112 is also affixed to the outer portion of the arm 56 and is also affixed to the deck 36 above the arm 56. The chain 112 thus limits downward movement of the broom 40 but does not support the broom 40 at all during its normal operation.

If the broom 40 strikes an immovable object such as a curb or wall, the object simply pushes the broom 40 inwardly under the deck 36 to prevent any damage to the object or the broom. During this movement, the bristles 50 still contact the surface with equal force and at the same 12-3 o'clock position to prevent damage to either the surface or the bristles. When the side broom of a conventional sweeper is engaged by an immovable object, the broom is pivoted about a horizontal axis so that its plane of rotation changes, with the result that the bristles at the outer edge of the broom tend to dig into the surface being swept, thereby frequently resulting in damage to both the bristles and the surface.

The particular supporting arrangement for the broom 40 has a further advantage. When the driven shaft 82 and the worm 100 are driven in the counterclockwise direction, the manner of engagement of the worm 100 and the worm gear 98 urges the gear housing 80 in a counter-

clockwise direction and also urges the arms 56 and 58 and the broom 40 in a similar or upward direction. Hence, the pressure of the bristles 50 on the surface being swept is less during normal rotation of the broom 40 than it would be if the broom were not being driven at all. If the broom 40 should now encounter a sudden rise in the surface as the sweeper moves along, the bristles 50 will have a tendency to engage the surface more fully so that the broom 40 requires more power. A greater amount of force is thus transmitted from the worm 100 to the worm gear 98, thereby increasing the upward force on the gear box 80, the arms 56 and 58, and the broom 40. Thus, the tendency for the increased engagement between the bristles and the surface, due to the rise in the surface, is thus overcome since the broom 40 is urged upwardly to decrease the pressure of the bristles 50 on the surface. The arm 56 and the broom 40 thus retain a higher position until the rise in the surface is passed. On the other hand, if the broom 40 should encounter a recess in the surface as the sweeper 20 moves therealong, the engagement of the bristles 50 and the surface will tend to be decreased, thus reducing the necessary power. The power transmitted from the worm 100 to the worm wheel 98 will then decrease and the force urging the broom 40 upwardly will decrease, with the result that the pressure of the broom 40 on the surface tends to increase. The arm 56 and the broom 40 thus assume a lower position until the recess is passed. Thus, with the particular drive arrangement for the broom 40, the broom pressure tends to remain the same when a rise is encountered and the broom position is raised and when a recess is encountered and the broom position is lowered. Therefore, the particular side broom drive arrangement minimizes the chance for the broom pressure to be either excessive or inadequate so that the wear on the bristles and the surface is decreased and the sweeping effectiveness of the bristles on the surface is increased.

The broom 40 is swung upwardly out of the way when not in use by means of a side broom handle 114 which is affixed to a side of the gear housing 80. The handle 114 extends upwardly through an opening 116 in a control handle panel 118 of the control board 38 so that it can be moved back and forth, parallel to the direction of movement of the sweeper 20, by the operator. The broom 40 can be held in an upper position when the handle 114 is moved to the rear of the opening 116 and is swung into a notch 120 which holds the handle in the rear position. When the handle is in its normal or operating position, as shown in FIG. 3, the pressure of the bristles 50 of the broom 40 on the surface being swept can be regulated by means of a side broom pressure spring 122 which is affixed to an upper portion of the handle 114 and also is attached to an upper end of an adjusting arm 124. The arm 124 is functionally integral with a second arm 126 and pivoted at an intermediate point to a pivot pin 128. The outer end of the second arm 126 is pivotally attached to an adjusting screw 130 which extends upwardly through the panel 116 and is pivotally engaged with an adjusting knob 132. When the knob 132 is screwed downwardly on the adjusting rod 130, the arms 126 and 124 are moved in a counterclockwise direction, thereby increasing the tension on the spring 122 and urging the handle 114 toward the rear to decrease the average pressure on the broom 40. The knob 132 can be turned in the opposite direction to decrease the tension on the spring 122 and thereby increase the pressure of the broom 40 on the surface.

When the handle 114 is moved to the rear position to raise the broom 40 from the surface, it is also desirable that the broom 40 be swung out of the way under the deck 36. To accomplish this, the gear box 80 is provided with a vertical supporting plate 134, to the upper

end of which is pivotally attached a side broom lever 136. The lower end of the lever 136 is connected to a lever spring 138 which is also attached to an ear 140 suitably located on the inner side of the gear box 80. The upper end of the lever 136 is horizontally aligned with a stop bar 142 which is affixed to the wall 104 at a height between the shaft 82 and the control board 38. When the handle 114 is moved toward its rear position, the upper end of the lever 136 abuts the stop bar 142 to cause the lever 136 to move in a clockwise direction. This causes the lower end of the lever 136 to move toward the left and put the spring 138 in tension, which places a rearward pull on the ear 140 and swings inwardly the yoke and the arms 56 and 58, along with the broom 40. Thus, the simple rearward movement of the handle 114 both raises the broom 40 and retracts it under the deck 36 of the sweeper 20. When the broom 40 is driven and again lowered, the contact of the bristles 50 with the surface causes the broom to swing again to its outer, sweeping position.

Various modifications of the above-described embodiment of the invention will be apparent to those skilled in the art and it is to be understood that such modifications can be made without departing from the scope of the invention, if within the spirit and tenor of the accompanying claims.

What I claim is:

1. A power sweeper for sweeping a large surface comprising, in combination, a main frame, a pair of rear wheels rotatably mounted on said frame, a steerable front wheel supporting a front portion of said frame, an operator's seat on said frame, a side broom including bristles and a backing plate, a generally vertical, side broom shaft, means on said side broom for connecting it to said shaft, said shaft being inclined slightly to the vertical so that the bristles of said side broom contact the surface principally at a position of 12-3 o'clock, taking the forward direction of movement of said sweeper as 12 o'clock, a bearing housing above said side broom and rotatably holding said side broom shaft, a first, generally horizontally-disposed, side broom arm attached to said bearing housing, a second, generally horizontally-disposed, side broom arm contiguous with said first side broom arm, means adjustably connecting said side broom arms, a yoke attached to said second side broom arm, said yoke having a pair of horizontally-disposed fork plates, one located above the other, each of said plates having annular wall means facing the other, a gear housing having a top wall and a bottom wall, each of said top and bottom walls having circular projections cooperating with said annular wall means of said fork plates to enable said fork plates, said arms, and said side broom to pivot in a horizontal plane around said gear housing, a vertically-disposed worm shaft rotatably mounted in said gear housing, a worm gear in said gear housing affixed to said vertical worm shaft, a generally horizontally-disposed, driven shaft rotatably supported by said main frame, and extending through and rotatably supporting said gear housing, a worm affixed to said driven shaft within said gear housing and meshing with said worm gear, means for driving said horizontal, driven shaft in a direction urging said side broom upwardly, a first sheave attached to said vertical worm shaft, a second sheave attached to said side broom shaft, belt means connecting said sheaves to drive said side broom in a direction urging said broom away from said sweeper when in contact with the surface, a first chain attached to said first arm and to said frame to limit outward movement of said side broom away from said frame, a second chain attached to said first arm and to said frame to limit downward movement of said side broom, a side broom handle attached to said gear housing and extending upwardly near said operator's seat, a side broom spring connected to said frame and to an upper portion of said handle, said side broom spring urging said handle rear-

wardly, means to adjust tension on said side broom spring, a supporting plate attached to said gear housing and extending upwardly therefrom on the side of said circular projections of said gear housing and said annular wall means of said fork plates toward the center of said sweeper, a side broom lever having an upper end and a lower end, an intermediate point of which is pivotally attached to said supporting plate, a stop bar held by said frame and aligned with the upper end of said lever, and a lever spring attached to the lower end of said lever and to said gear housing on the same side thereof as said supporting plate, said stop bar urging the upper end of said lever forwardly to place said lever spring in tension to urge said arms and said broom inwardly under said sweeper when said side broom handle is pulled rearwardly.

2. A power sweeper for sweeping a large surface comprising, in combination, a main frame, a pair of rear wheels rotatably mounted on said frame, a steerable front wheel supporting a front portion of said frame, an operator's seat on said frame, a side broom including bristles and a backing plate, a generally vertical, side broom shaft, means on said side broom for connecting it to said shaft, bearing means for rotatably supporting said side broom shaft about a generally vertical axis, arm means connected to said side broom shaft-supporting means, a yoke attached to said arm means, a gear housing rotatably connected to said yoke for movement of said yoke about a vertical axis whereby said arm means, said bearing means, and said side broom can pivot in a generally horizontal plane around said gear housing, a vertically-disposed worm shaft rotatably mounted in said gear housing, a worm gear in said gear housing affixed to said vertical worm shaft, a generally horizontally-disposed, driven shaft rotatably supported by said frame, and extending through and rotatably supporting said gear housing for pivotal movement about a horizontal axis, a worm affixed to said driven shaft within said gear housing and meshing with said worm gear, means for driving said driven shaft in a direction urging said worm gear, said worm shaft, said gear housing, said arm means, said yoke, and said side broom upwardly around said driven shaft, sheave and belt means connecting said vertical worm shaft and said side broom shaft whereby said side broom is driven in a direction urging said broom away from said sweeper when in contact with the surface, and means associated with said frame to limit outward movement of said side broom.

3. A power sweeper for sweeping a large surface comprising, in combination, a main frame, wheel means rotatably mounted on said frame, a side broom, a generally vertical, side broom shaft, means on said side broom for connecting it to said shaft, bearing means for rotatably supporting said side broom shaft about a generally vertical axis, a gear housing, means pivotally connecting said bearing means to said gear housing for pivotal movement of said connecting means around a vertical axis, whereby said pivot means, said bearing means, and said side broom can pivot in a generally horizontal plane around said gear housing, a gear shaft rotatably mounted in said gear housing, a first gear in said gear housing affixed to said gear shaft, a generally horizontally-disposed, driven shaft rotatably supported by said frame, and extending through and rotatably supporting said gear housing for movement about a horizontal axis, a second gear affixed to said driven shaft within said gear housing and meshing with said first gear, means for driving said driven shaft in a direction urging said first gear, said gear shaft, said gear housing, said pivotal connecting means, and said side broom upwardly around said driven shaft, means connecting said gear shaft and said side broom shaft whereby said side broom is driven in a direction urging said broom away from said sweeper when in contact with the surface, a side broom handle attached to said gear housing to raise said broom, spring means con-

nected to said handle, and means adjustably connecting said spring means to said frame to adjust tension on said spring to vary the pressure of said broom on the surface.

4. A power sweeper for sweeping a large surface comprising, in combination, a main frame, wheel means rotatably mounted on said frame, a side broom, a generally vertical, side broom shaft, means on said side broom for connecting it to said shaft, bearing means for rotatably supporting said side broom shaft about a generally vertical axis, a gear housing, means pivotally connecting said bearing means to said gear housing for pivotal movement of said connecting means about a vertical axis, whereby said pivot means, said bearing means, and said side broom can pivot in a generally horizontal plane around said gear housing, a gear shaft rotatably mounted in said gear housing, a first gear in said gear housing affixed to said gear shaft, a driven shaft rotatably supported by said frame and extending through said gear housing, said driven shaft being horizontally disposed and located transversely to the forward direction of movement of said sweeper, a second gear affixed to said driven shaft within said gear housing and meshing with said first gear, means for driving said driven shaft in a direction urging said side broom upwardly, and means connecting said gear shaft and said side broom shaft whereby said side broom is driven when said gear shaft is rotated.

5. A power sweeper for sweeping a large surface comprising, in combination, a main frame, wheel means rotatably mounted on said frame, a side broom, a generally vertical, side broom shaft, means on said side broom for connecting it to said shaft, bearing means for rotatably supporting said side broom shaft, a pivotable housing, means mounted on said frame for pivotally supporting said housing in a vertical plane, arm means connecting said housing and said bearing means whereby said side broom can be pivoted in a vertical plane with said housing, said connecting means being pivotally mounted on said housing to enable said connecting means, said bearing means, and said side broom to pivot in a hori-

10 15 20 25

zontal plane around said housing, a side broom handle attached to said housing to raise said side broom, a spring having one end attached to said housing toward the center of said sweeper from the pivotal connection of the pivot connecting means, a lever pivotally supported by said gear housing with one end connected to the other end of said spring, and means for engaging and pivoting said lever to place said spring under tension only when said broom is raised, to move said broom inwardly under said sweeper.

6. A power sweeper according to claim 3 characterized by a second spring attached to said housing toward the center of said sweeper from said pivot means, and means for placing said second spring under tension when said broom is raised to move said broom inwardly under said sweeper.
